(57) **CLAIM**

The ornamental design for an avionics flight display, as shown and described.

DESCRIPTION

FIG. 1 is a front perspective view of an avionics flight display according to the present invention, with the broken line shown for illustrative purposes only and forming no part of the claimed design;

FIG. 2 is a front elevational view thereof;

FIG. 3 is a top plan view thereof;

FIG. 4 is a bottom plan view thereof;

FIG. 5 is a left side view thereof; and,

FIG. 6 is a right side view thereof.
